(57) **CLAIM**

The ornamental design for an ophthalmic equipment stand, as shown and described.

DESCRIPTION

FIG. 1 is a perspective view of an ophthalmic equipment stand showing my new design;

FIG. 2 is a front elevation view thereof;

FIG. 3 is a back elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is a second perspective view of the ophthalmic equipment stand of FIG. 1 shown in a position of use with ophthalmic equipment drawn in broken lines.

The broken lines in the drawings are for the purpose of illustrating portions of the ophthalmic equipment stand that form no part of the claimed design. The ophthalmic equipment shown in broken lines in FIG. 8 depicts environment and forms no part of the claimed design.
